Int. Cl. D25—01

U.S. Cl. D13—1

FIG. 1 is a top view of an ornamental airport flooring wherein the parallel lines in two sectors represent the exclusive chordal direction of the narrow slat wooden flooring that extends all along the ornamental airport flooring and is disposed in each sector to have a direction approximately perpendicular to a radial line substantially as shown;

FIG. 2 is an exploded view of the portion of the ornamental airport flooring pattern shown in the circle of FIG. 1 wherein the shading represents conventional wood graining.

I claim:

The ornamental design for an ornamental airport flooring, substantially as shown and described.
